G. FRINK.
CABLEWAY CARRIAGE,
FILED JUNE 2, 1921.

FIG. 1

FIG. 2

FIG. 3

Inventor
Gerald Frink

By H. C. L. Reynolds.

Attorney

UNITED STATES PATENT OFFICE.

GERALD FRINK, OF SEATTLE, WASHINGTON.

CABLEWAY CARRIAGE.

Application filed June 2, 1921. Serial No. 474,492.

To all whom it may concern:

Be it known that I, GERALD FRINK, a citizen of the United States of America, and resident of the city of Seattle, in the county 5 of King and State of Washington, have invented certain new and useful Improvements in Cableway Carriages, of which the following is a specification.

My invention relates to cableway carriages and consists of certain constructions which are designed to better adapt the carriage for carrying heavy loads by distributing the load over more wheels, and also to decrease the angle of bend of the cables in 15 passing over the wheels.

A further object of my invention is to provide such supports for and to so run the hoisting cables over them, as to avoid bending this cable alternately in opposite directions, thereby reducing the internal friction 20 and wear in such cables.

In the accompanying drawings I have shown my invention in forms of construction which well illustrate the principles of 25 my invention and in the form which is now preferred by me.

Figure 1 shows a cableway carriage having my invention embodied therein, one side plate being removed to better show the position and relation of the wheels.

Figure 2 is a vertical transverse section through that part of the carriage containing the fall rope pulleys.

Figure 3 is a view similar to that of 35 Figure 1 but modified to fit a double or looped main line or trackway cable.

The ordinary cableway carriage, if running on a single trackway or main cable, has two pulleys which support the carriage upon 40 the cable. In heavy duty work this produces very great pressure between the cable and the pulleys, often sufficient in intensity to somewhat deform or compress the cable. Recognizing this fact it has been my object 45 to provide a plan and means whereby the number of carrying wheels may be increased, thereby reducing the pressure of each upon the cable, and also to provide means whereby the hoist cable will be bent 50 only in one direction.

The first mentioned result, is secured by increasing the number of wheels which run upon the cable. In Figure 1 of the drawings I have shown a carriage containing three 55 carrying wheels, 1, 2 and 3. If three wheels be journaled in a rigid frame, an equal dis-

tribution of weight will not be secured. If the bearing edges of the wheels be placed in a straight line, the center wheel will hardly carry any load, as to carry any load a wheel 60 must deflect the cable.

Even if the center wheel, as 2, be offset, while it will carry some load, an equal distribution of the load will not be secured for the reason that the angular relation of the 65 parts of the cable at opposite sides of the carriage will vary with the sag in the cable and also with the position of the carriage lengthwise of the cable.

To secure equal loads upon the carrying 70 wheels at all times and under all conditions, I have mounted them in equalizing levers 4 and 40 and support the other parts of the carriage from these levers by links, as 5, 5, which are connected with the equalizing 75 levers at points which are one third of the distance from the axis of the outer wheels 1 and 3 to the center wheel 2. In this way each wheel must carry one third of the load, whatever the sag of the cable, within a 80 reasonable range of variation.

By using compensating or equalizing 85 levers on the same principle, a larger number than three carrying wheels may be employed. This is so obvious that specific illustration thereof is hardly thought necessary. The construction of the other parts of the carriage may also be varied. This part of the carriage as shown in the drawings has two side plates 6, between which are journaled four sheave wheels 7, 70, 8, and 80. The drawings show the outer plate of the carriage removed to better show these wheels 90 and the manner of disposing of the hoist rope.

In the type of carriage wherein the hoist 95 rope is a running line, that is passes through the carriage, and has a hoist block in a depending loop of the line, as 9, it passes about two pulleys as 7 and 8, and between these 100 about the hoist block 9, this bending the line three times in successively opposite directions. Such opposite bending of the line is much harder upon it, producing much greater internal friction than where the 105 bending is all in the same direction.

Instead of following the above plan I provide two additional sheave wheels or pulleys, 70 and 80, crossing the two parts of the line 11 in their passage between the upper 110 and the lower sheaves. By this expedient the bending of the line is everywhere in the

same direction and also, the angle of bend when passing about the sheaves in the carriage is reduced.

To prevent friction between the two crossing parts of the rope, the sheaves 7, 70, 8 and 80 of the carriage are of double width having the line receiving grooves 71 and 81 at one side, the other side being provided with a flange 78, preferably slightly coned so as to deflect the line if it ever bears thereon, into the proper groove. The sheaves 7 and 70 have their grooves placed at one side of the carriage and the sheaves 8 and 80 at the opposite side. All these sheaves may be alike in construction, two being turned oppositely to the other two. By this expedient the crossing parts of the line 11 are prevented from rubbing together.

In Figure 3 I have shown how a carriage embodying the principles of my invention might be constructed to apply to a double or looped main line system. The lines 10 and 10' are both main or trackway lines. A second set of carrying sheaves 1', 2' and 3' are provided for line 10' and journaled in equalizing bars 4' and 40' and these are connected with the equalizing bars of the other like system by links 5'.

The lines 13 and 14, represent haul and back haul lines.

With the carrying sheaves of the carriage mounted in equalizing bars as shown, each sheave at all times and under all conditions,

carries its proportion of the load. The central sheave will drop below the line connecting the outer sheave and the amount of such offset will vary with the sag of the line. With a very taut line and a small sag the offset will be slight, but with a large sag in the line the offset will be increased. Within the limits of possible relative movement between the sheaves, the offset will at all times be such that the angle of bend of the line in passing each sheave will be uniform.

What I claim as my invention is:

1. A cableway carriage having four guide pulleys for a running hoist rope positioned to guide the rope coming from opposite sides to cross within the carriage.

2. A cableway carriage having four guide pulleys for a running line positioned at the corners of a quadrangle, the pulleys of two opposite corners having their line grooves offset towards one side of the carriage and those at the other opposite corners offset towards the other side of the carriage.

3. In combination, a cableway carriage, a running line, a block in a loop of said line, two pairs of guide pulleys for said line journaled in the carriage to guide the line coming from opposite sides of the carriage to cross and in laterally offset planes.

Signed at Seattle, King County, Washington this 27 day of May 1921.

GERALD FRINK.
